To all whom it may concern:

Be it known that I, Jules Jackson, a citizen of the United States, residing in Great Neck, Long Island, county of Nassau, and State of New York, have invented a new, original, and ornamental Design for a Carded Two-Piece Hair Ornament, of which the following is a specification, reference being had to the accompanying drawing, forming part thereof.

The area lined in black gives the appearance of a lock of hair.

I claim:

The ornamental design for a carded two-piece hair ornament, as shown.

JULES JACKSON.
